J. BRADLEY

ELECTRIC SWITCH

Filed Dec. 28, 1923

Fig. 1.

Patented July 14, 1925.

1,545,579

UNITED STATES PATENT OFFICE.

JOSIAH BRADLEY, OF BROOKLYN, NEW YORK.

ELECTRIC SWITCH.

Application filed December 28, 1923. Serial No. 683,133.

To all whom it may concern:

Be it known that I, JOSIAH BRADLEY, a citizen of the United States, residing in the borough of Brooklyn, county of Kings, city and State of New York, have invented an Improvement in Electric Switches, of which the following is a specification.

My present invention relates to an electric switch and more particularly to that type of switch in which an electric circuit is made and broken through a liquid contact. In switches of this type it has been customary heretofore to employ mercury as the liquid contact member in conjunction with a terminal which is suitably moved into and out of the mercury for making and breaking the electric circuit. The movable contact as heretofore employed is found in practice to accumulate a coating by oxidation or other-
wise, for example by the adhesion of foreign particles thereto so that sooner or later the connection between the movable contact and the liquid contact is impaired to such an extent as to interfere with the efficient opera-
tion of the switch. The object of my present invention is the provision, in an electric switch of a movable contact member so con-
structed that a portion of the liquid contact member adheres thereto when the movable contact member is withdrawn from the liquid contact member in opening a circuit so that when the movable contact member is reinserted into the liquid contact member in again making the circuit there is a sufficient quantity of the liquid contact member car-
ried by the movable contact member to re-
unite with the liquid contact member in re-
making the circuit to cause the switch to op-
erate efficiently and without attention for an exceedingly long period. In carrying out the invention, therefore, I employ a movable contact member which is constructed in any desired way to provide a plurality of slightly spaced tongues or fingers having interme-
diate recesses or grooves for permitting suffi-
cient adhesion between the parts of the movable contact member and the liquid contact member to accomplish the purposes desired. Also in carrying out the invention, particu-
larly where mercury is employed as the liquid contact member of the switch, I prefer to use a stem or link to which the movable contact member is connected and which is made of a material of such a nature that there is substantially no adhesion between the mercury and this member of the switch.

For this purpose, I have found that dur-
lumin may be employed to advantage.

In the drawing:

Fig. 1 is a transverse section and partial elevation illustrating an electric switch and an apparatus for operating the same made in accordance with my present invention.

Fig. 2 is an enlarged section on line 2—2, Fig. 1.

Fig. 3 is an enlarged longitudinal section of the stem or link member and the movable contact member associated therewith, and

Fig. 4 is a perspective view of the stem or link member and also the movable contact member showing these parts in a sep-
arated relationship.

By reference to the drawing it will be seen that in carrying out my invention I employ a receptacle 10 made of any suitable ma-
terial and adapted to contain a quantity of mercury 11 or other similar material in liquid form adapted to be employed as the liquid contact of a switch for opening and closing an electric circuit. As illustrated, I also prefer to employ a suitable liquid cover-
ing for the mercury, as for example oil as indicated at 12 to prevent the mercury from coming into contact with the air and thus conserving the same as far as possible. The receptacle 10 is provided with a terminal 13 extending into the same so as to lie within the mercury contact, while exteriorly of the receptacle the same comprises a binding post 14. The receptacle may also be fitted with a suitable top or cover 15 which is removable and which may be secured thereto in any suitable manner.

The movable contact to which my invention more particularly relates comprises, as illustrated, a pair of contact plates 17, 18. These plates may be riveted together as indicated at 19 and preferably include extensions 20 and 21 forming clips by which the movable contact may be connected to a stem or plunger as hereinafter described. The contact plates 17 and 18 are so formed as to have the major portions thereof slightly separated so as to form an intervening relatively narrow space. Also as indicated, the extremities of these contact plates are provided with tongues 17', 18' which are slightly separated from each other so as to leave intervening notches. The space between the separated portions of the contact plates and the notches between the tongues at the extremities thereof are so formed as to receive and retain a

part of the mercury or other liquid contact of the switch when the contact plate is removed therefrom so that the closing of the circuit will be facilitated by the movable contact plate being reimmersed in the mercury or other liquid contact member. This contact member is preferably made of copper and hence is a solid contact in contradistinction to the mercury as a liquid contact.

10 The movable contact member is connected to and carried by a stem or plunger 22. This stem 22 at its free end 23 is notched as indicated at 24 and provided with an aperture 25 adapted to receive the inturned ends of the extensions 20, 21 of the clip portion of the movable contact with the ends 23 of the stem abutting against shoulders 26 provided for this purpose on the movable contact member in order to secure 15 the contact member yieldingly to the stem and to maintain the same in position thereon. The stem or plunger 22 passes through a hole 27 provided therefor in the cover 15 and at its outer end is pivotally connected 20 to 28 to a rocker lever 29. The end of the stem 22 preferably lies between the side of the rocker lever and a conductor plate 31 secured to one face of the rocker lever by rivets 32, 33. The rocker lever 29 is 25 mounted to oscillate on a shaft 34 which may be supported by any suitable means. On the shaft 34 there is a sleeve 35 of insulating material which is adapted to receive a socket 36 fitting into an aperture 30 provided for this purpose in the rocker lever 29. The sleeve 35 and the socket 36 are suitably shouldered to engage spring washers 37 and 38, the latter engaging with the conductor plate 31 and the parts being 35 maintained in this relationship and in suitable positions relatively to each other by means of a set screw 39 or otherwise.

At the end of the rocker lever 29 opposite that to which it is pivotally connected to 40 the stem 22 there is an insulating lug 40. This lug 40 is adapted to fit in a recess 41 provided therefor at the extremity of an operating lever 42. This lever 42 as illustrated may be pivotally mounted on a suitable support 43 and the support secured in a base or frame 44. The lever 42 may be operated from a button 45 or otherwise but this means of operating the switch is merely 45 illustrative.

50 The conductor plate 36 carried by the rocker lever may be fitted with a terminal 46 connected by a lead 47 to a terminal 48 of a lamp socket 49 adapted to receive a lamp 50, while the other terminal of the socket 49 as indicated at 51 may be connected by a lead 52 to one terminal of a battery or other source of energy 53, and the other terminal of the battery connected by a lead 54 to the binding post 14. It will 55 be understood, however, that the closing of

the switch in a lamp circuit is also merely illustrative as the switch may be employed for innumerable purposes, for example in opening and closing circuits in electric keyboards for organs and pianos, opening and closing the switch in linotype machines, electric display signs and obvious other devices in which an electric circuit is opened and closed with more or less frequency and rapidity.

In carrying out the invention the stem or plunger member 22 to which the movable contact is secured is preferably made of duralumin having a composition of approximately three and five-tenths percent copper, two-tenths percent magnesium, four-tenths percent manganese and ninety-two percent aluminum. The use of the stem or plunger member of this composition in a switch in which mercury is employed is particularly desirable because I have found, as hereinbefore stated, that the stem made of duralumin of the composition indicated is not susceptible to any action by the mercury with which it comes in contact and consequently the mercury will not spread over the surface of the same so as to eventually cover the stem and extend to the pivotal point so as to interfere with the conductor members forming part of the electric circuit. Moreover, as hereinbefore stated, my present invention relates to this feature and to the construction of the movable contact member.

From the foregoing it will be understood that in carrying out my invention I have provided an electric contact that does not require cleaning inasmuch as the contact tip or point is constructed as shown and described, or in an equivalent manner, to retain a quantity of the liquid contact when removed therefrom to open the circuit sufficient to reunite with the liquid contact when being re-immersed therein to efficiently reclose the circuit; and also by the use of the duralumin stem or plunger the tendency of the mercury or other liquid contact to spread thereon is obviated.

I claim as my invention:

1. In an electric switch, a liquid contact member, a solid contact member having a plurality of parts separated to provide an intermediate space adapted to retain a portion of the liquid contact member therein when withdrawn from the same.

2. In an electric switch, a liquid contact member, a solid contact member having a plurality of parts separated to provide an intermediate space adapted to retain a portion of the liquid contact member therein when withdrawn from the same, and means for moving the solid contact member into and out of the liquid contact member to make and break an electric circuit.

3. In an electric switch, a liquid contact

- member, a solid contact member having a plurality of tongues with intermediate spaces adapted to retain a portion of the liquid contact member therein when withdrawn from the same. 5
4. In an electric switch, a liquid contact member, a solid contact member having a plurality of tongues with intermediate spaces adapted to retain a portion of the liquid contact member therein when withdrawn from the same, and means for moving the solid contact member into and out of the liquid contact member to make and break an electric circuit. 10
5. In an electric switch, a liquid contact member, a solid contact member having a plurality of separated parts each having a plurality of tongues whereby intermediate spaces are provided for retaining a part of the liquid contact member when withdrawn therefrom. 20
6. In an electric switch, a liquid contact member, a solid contact member having a plurality of separated parts each having a plurality of tongues whereby intermediate spaces are provided for retaining a part of the liquid contact member when withdrawn therefrom, and means for moving the solid contact member into and out of the liquid contact member to make and break an electric circuit. 25
7. In an electric switch, a liquid contact member, a solid contact member comprising separated plates each having a plurality of tongues at its extremity for providing a space between the plates and slots between the tongues adapted to retain a part of the liquid contact member therein when withdrawn from the same. 35
8. In an electric switch, a liquid contact member, a solid contact member comprising separated plates each having a plurality of tongues at its extremity for providing a space between the plates and slots between the tongues adapted to retain a part of the liquid contact member therein when withdrawn from the same, and means for mov- 40
- ing the solid contact member into and out of the liquid contact member to make and break an electric circuit. 50
9. In an electric switch, a liquid contact member, a solid contact member, a plunger stem to which the said solid contact member is removably attached, means for actuating the plunger stem for moving the solid contact member into and out of the said liquid contact member, the said solid contact member comprising separated plates having a space between the same adapted to retain a part of the liquid contact member therein 55 when withdrawn from the same. 60
10. In an electric switch, a liquid contact member, a solid contact member, a plunger stem to which the said solid contact member is removably attached, means for actuating the plunger stem for moving the solid contact member into and out of the said liquid contact member, the said solid contact member comprising separated plates each having a plurality of tongues at its extremity providing a space between the plates and slots between the tongues adapted to retain a part of the liquid contact member therein when withdrawn from the same. 65
11. In an electric switch, a liquid contact member, a contact member having a plurality of spaced parts, a plunger stem made of a material on which the liquid contact member does not spread, and means for actuating the plunger stem for moving the contact member into and out of the liquid contact member to make and break an electric circuit. 70
12. In an electric switch, a mercury contact member, a contact member having a plurality of spaced parts, a plunger stem of duralumin to which the contact member is removably connected, and means for reciprocating the plunger stem to move the contact member into and out of the mercury contact member. 85

Signed by me this 22nd day of December, 1923.

JOSIAH BRADLEY.
